UNITED STATES PATENT OFFICE

149,553

DESIGN FOR A LOCOMOTIVE BODY

Fritz Paul Grutzner, Beloit, Wis., assignor to Fairbanks, Morse & Co., Chicago, Ill., a corporation of Illinois

Application October 5, 1946, Serial No. 133,800

Term of patent 14 years

(Cl. D66—1)

To all whom it may concern:

Be it known that I, Fritz Paul Grutzner, a citizen of the United States, residing at Beloit, in the county of Rock and State of Wisconsin, have invented a new, original, and ornamental Design for a Locomotive Body, of which the following is a specification, reference being had to the accompanying drawing, forming part thereof.

In the drawing:

Fig. 1 is a view in side elevation of a locomotive body, showing my new design;

Fig. 2 is a top plan view of the design;

Fig. 3 is an end elevation at the cab end of the locomotive body, being at the left as viewed in Fig. 1, and

Fig. 4 is an end elevation of the opposite end of the locomotive body.

Fig. 5 is a side perspective view of the locomotive body.

The side elevational view opposite to that of Fig. 1, is substantially identical with the view of Fig. 1.

The dotted line showing in Figs. 1, 3, 4 and 5 is for illustrative purposes only.

I claim:

The ornamental design for a locomotive body, as shown and described.

FRITZ PAUL GRUTZNER.
